ALEXANDER MCKENZIE, OF NEWPORT, KENTUCKY, ASSIGNOR TO HIMSELF
AND WILLIAM C. DAVIS, OF SAME PLACE.

Letters Patent No. 65,252, dated May 28, 1867.

IMPROVED PADDLE-WHEEL.

The Schedule referred to in these Letters Patent and making part of the same.

TO WHOM IT MAY CONCERN:

Be it known that I, ALEXANDER MCKENZIE, of Newport, in the county of Campbell, and State of Kentucky, have invented a new and useful improvement in Steamboat Paddle-Wheels; and I hereby declare the following to be a full, clear, and exact description thereof, reference being had to the accompanying drawings, making part of this specification.

The object of this invention is to provide a paddle-wheel for steamboats possessing several prominent advantages over those in ordinary use. In the accompanying drawings—

Figure 1 is a perspective view of a paddle-wheel embodying my improvements, as seen from the outside, in the form for a side-wheel steamer.

Figure 2 is a diagram, showing how a modification of the same is applied to a stern-wheel steamer.
A is the framework of the wheel, consisting mainly of the radial arms B, inclined secondary arms C, and brace-rings E, all being secured to the paddle-shaft F. Upon the outer ends of the arms C are secured the floats or buckets G, by means of bevel-blocks H and staple-bolts I. The arms on each of the two or more separate series or planes stand in such relative position to those in the other planes that the buckets G are considerably inclined from the direction of the paddle-shaft, although being from end to end equidistant from it, so that, as the paddle revolves, (the direction of which revolution is shown by arrows,) the buckets will not enter the water from end to end at the same time, but gradually, so that while the one bucket is on the point of becoming submerged, the next following will have commenced to enter the water, thus avoiding the exceedingly disagreeable and destructive jar incident to the ordinary wheel having buckets at right angles in their length to the side of the boat. It will be observed that the frame of the wheel has a novel form of construction in respect to the arms, the same being formed of two pieces B and C, the latter being secured at about its mid-length to the former, carrying at the outer end the bucket or paddle, and at the inner end being secured to the preceding radial arm B. This arrangement gives great strength and firmness to the framework of my wheel, and materially lessens the strain of the buckets upon the frame, as the direction in which the resistance will bear upon the arms B will be almost as much an end strain as a side strain upon the said arms. This arrangement of inclined secondary or sub-arms C also possesses advantages in giving the buckets the right direction to avoid raising the water when leaving the same, which throwing up of water not only involves a very considerable loss of power, but also rots the wood-work behind the wheel. The buckets on an ordinary paddle-wheel, if placed in the radially inclined position, or the necessary position to leave the water freely without raising the same, would not only involve a cutting away of the arms to a bevel at the ends, or some other means for the purpose, but the blow upon the water incident to such position would be very objectionable; whereas, with my paddle-wheel, owing to the gradual submergence of the buckets, such objection would be obviated. It is also claimed that my wheel will be much less liable to damage in ice or drift, as the position of the buckets or paddles would tend to push the obstructions aside rather than to strike them with a heavy downward blow, as is the case with the ordinary wheel now in use. The jar inseparable from the ordinary wheel shakes the joints not only of the machinery, but of the whole boat, shakes bearings loose, and cuts out the journal-boxes, making it very desirable that said jar should be avoided as much as possible. This inclination of the buckets will be found of great advantage in case of boats grounding on their bows, as by the reversal of the paddle-wheel the paddles would depress the stern by the downward draught the buckets would have upon the water, which, together with the water forced, by the lateral inclination of the paddles, under the boat, would raise the bow, and usually clear said boat from the bar or obstruction without the use of spars, thus saving much loss of time and often much damage to the boat.

The improvement I claim as equally applicable to stern as to side-wheel boats, by in a manner duplicating the wheel, or arranging the buckets on the double inclination, as seen in fig. 2.

I claim herein as new, and of my invention—

The arrangement of inclined blades or buckets G, radial arms B, oblique secondary arms C, and brace-rings E, substantially as and for the purpose set forth.

In testimony of which invention I hereunto set my hand.

ALEXANDER MCKENZIE.
